WITNESS:

UNITED STATES PATENT OFFICE.

THOMAS CORRIGAN, OF MARINETTE, WISCONSIN.

MOTOR STAND.

Application filed February 21, 1924. Serial No. 694,429.

To all whom it may concern:

Be it known that I, THOMAS CORRIGAN, a citizen of the United States, residing at Marinette, in the county of Marinette and 5 State of Wisconsin, have invented new and useful Improvements in Motor Stands, of which the following is a specification.

This invention relates to supporting stands for motors, and has for its object the 10 provision of a stand for supporting and holding the transmission assembly of a Ford automobile engine while repairs, replacements or adjustments are being made.

An important object is the provision of 15 a stand of this character so constructed that the transmission assembly may be held in any one of four possible positions, depending upon the nature of the operation to be effected the device acting to save considerable time, labor and annoyance when repairing.

An additional object is the provision of a 20 device of this character which will be simple and inexpensive in manufacture, easy to use, efficient and durable in service and a general improvement in the art.

With the above and other objects and advantages in view the invention consists in 25 the details of construction to be hereinafter more fully described and claimed and illustrated in the accompanying drawings, in which:

Figure 1 is a side elevation of the device 30 showing the fly wheel holding means in one position,

Figure 2 is a side elevation showing the fly wheel holding means in a different position,

Figure 3 is a top plan view with the parts 35 arranged as in Figure 2,

Figure 4 is a detail section on the line 40 4—4 of Figure 2,

Figure 5 is a detail edge view of the fly 45 wheel clamp showing the hinge connection thereof.

Figure 6 is a sectional view of the hinge 50 connection of the clamp.

Referring more particularly to the drawings, the numeral 10 designates a pair of 55 elongated bars to which are secured the lower ends of uprights 11 which are provided at their upper ends with recesses or notches 12. Intermediate their ends, the uprights are connected by a transverse member 13 which may be a suitable length of a

wooden or metal bar. In fact all the bars and uprights may be of channel or angle iron of any desired cross sectional configuration and the dimensions may be such as to insure proper strength, there being no 60 limitations however in these respects. The upper end portion of one upright is provided with a hole 14 for the passage of a pin 15 carried by a chain 16 and provided for a purpose to be described. 65

In connection with this supporting structure I make use of a clamp which comprises a pair of semi-circular sections 17 which mate to define a circle corresponding substantially to the size of the fly wheel of a 70 Ford transmission. These sections are hingedly connected at one end as shown at 18 and are formed at their other ends with outstanding ears 19 through which passes a clamping bolt 20 equipped with a nut 21. 75 Carried by the clamp at diametrically opposite points are handles 22 preferably cast integrally with the clamp sections. These handles are adapted to seat within the recesses or notches 12. 80

Disposed on one handle member 22 is a collar 23 preferably cast integrally with the clamp section, and this collar is provided with a plurality of holes 25 so arranged as to receive the pin 15 as will be explained. 85 In actual practice, it is intended that two fly wheel cap screws with shoulders be included with each stand, these cap screws being used to hold the transmission shaft in place while the transmission disk drum is 90 driven into place.

To explain the use of the device, it is necessary to state that the engine and transmission of a Ford car is removed bodily when repairs to the transmission are required. Assuming that the power plant has 95 been removed from the car and that it is entirely free from the crank case and transmission case, the operator takes the clamp and engages it about the fly wheel A. The 100 nut 21 is tightened so that the clamp will grip the fly wheel very firmly so that slipping will be positively prevented. The handle members 22 facilitate handling or turning of the fly wheel, while the power plant 105 is supported on a bench or the like, so that access may be readily had to the cap screws which hold the fly wheel to the crank shaft. After the cap screws have been removed, 110 the entire transmission may be lifted by

grasping the handles 22. The transmission held by the clamp is then supported from my stand by engaging the handle members 22 in the recesses or notches 12 at the upper ends of the uprights 11. The entire transmission assembly may then be swung into any desired position and held by engaging the pin 15 through the selected one of the holes 25. In the present instance four of such holes are shown as the four possible positions are sufficient to permit access to all parts of the transmission for disassembling and reassembling. After the necessary repairs have been made, the pin 15 is disengaged from the holes and the reassembled transmission carried by means of the handles 22, so that it may be again connected with the motor crank shaft.

From the foregoing description and a study of the drawings it will be apparent that I have thus provided a simply constructed, inexpensive and highly efficient stand which will greatly facilitate repairing and which will save time, labor and annoyance in addition to having the other great advantage of avoiding picking up of cotter pins and other similar small objects by the magnets on the fly wheel. The device is bound to be satisfactory in every way and should therefore recommend itself

to those having occasion to employ its services.

While I have shown and described the preferred embodiment of my invention it is of course to be understood that I reserve the right to make such changes in the form, construction and arrangement of parts as will not depart from the spirit of the invention or the scope of the subjoined claim.

Having thus described my invention I claim:

In a device of the character described, a base including side members, uprights connected with and rising from said base members and having their upper ends formed with downwardly extending notches, in combination with a clamp device including hingedly connected sections and provided with means for effecting clamping in embracing relation to the fly-wheel of a motor, said clamped sections being provided with trunnions rotatably engaged within said notches, and means carried by one of the uprights and cooperating with one of the clamping members for maintaining the clamping member in a rotatably adjusted position.

In testimony whereof I affix my signature.

THOMAS CORRIGAN.
